UNITED STATES PATENT OFFICE

FREDERICK T. HOPE, OF SEATTLE, WASHINGTON

SHAVING DEVICE

Application filed October 7, 1929. Serial No. 397,836.

This invention relates to an improvement in shaving devices, and has for an object, generally stated, the provision of novel apparatus of this character effectively adapted for more advantageous and efficient application to the demands of an operator than similar devices heretofore conceived.

A more specific object of the invention is the provision of a device of this character 10 peculiarly adapted to increase the cutting facilities from the respective blade insertions.

A further object of the invention is the provision of novel means peculiarly adapted to combine, in a compact assembly with the 15 improved blade structure, a soap cartridge effectively co-operative to a lather forming brush.

Further objects and advantages will become apparent in the following description, 20 the invention consisting in the novel construction, adaptation and combination of parts hereinafter described and claimed.

In the drawings, Figure 1 is a side elevation of apparatus representative of the now 25 preferred embodiment of my invention; Fig. 2 is a longitudinal vertical section thereof; Fig. 3 is a plan view of the razor head; Fig. 4 is a plan view of the improved blade used therewith; and Fig. 5 is a vertical transverse 30 section, substantially on lines 5—5 of Fig. 2, illustrative of the soap discharging piston and barrel housing therefor.

Reference being had to the drawings, the 35 numeral 6 represents generally, the assembly of my novel shaving device structure, comprising the co-operatively arranged demountable head 7 and a barrel handle 8 therefor.

While said head, as illustrated, utilizes a 40 conventional manner of crimping an interposed plane faced pliable metallic blade 9 between a cap piece 10 and a backing plate 11, the structural configuration of said co-operative parts is a part of the present inventive conception.

To which end, the aforesaid cap piece and 45 plate, 10, 11, respectively, are suitably cast to a substantially cross-shaped, generally designated by the word Maltese, convex conformation. Projecting studs 12, integrally 50 arranged to the cap, are engaged through

companion annulets of the blade 9 and backing plate 11, the latter being compressed, as by a tubular axially disposed cap-piece stem 13 engaging internal screw threads 14 of the shank 15 of barrel 8, to engage said plate 55 against a shoulder 16 of the shank.

The assembled head presents the cutting edges 20 of the blade substantially intermediate the beveled end extremities 21 of respective cap wings 22 and the serrated end 40 guard-forming teeth 23 of the backing plate.

The annulets of said blade (Fig. 4) desirably form an enlarged eye 17, struck from the inner extremities of the radially disposed outwardly diverging channels 18, in a manner to facilitate ready pliability of the blade 65 on the plane of a line conceived through the axis of co-operative throat forming annulets of the respective blade wings 19.

I provide, in centrical disposition to the 70 surface 24 of the cap piece, a rubber brush 25, the body of which is suitably retained by inwardly diverging side walls of a recess 27 of said cap. In aligned disposition to the bore of the cap stem 13, said brush provides 75 a soap discharge 28, communicatively arranged, through the barrel shank 15, to the chamber 30 of the barrel.

Diametrically oppositely disposed slots 31 in said chamber engage, for relative movement longitudinally thereof, ears 32 of a piston member 33, screw threads centrically of which are engageable to actuate the same through the medium of a rotatable screw 80 threaded rod 34. The outer end of said rod, 85 I indicate as being rigidly attached to a knurled finger piece 35, rotatably supported by the inwardly disposed flange lip 36 engaging an annular channel disposed peripherally about a crown 38, removably secured to 90 the barrel.

For insertion within the chamber 30, I provide a substantially tube-shaped plastic cartridge 39 of soap, passing the rod 34 through a longitudinally disposed aperture there- 95 through.

In operation, subsequent to insertion of a soap cartridge by removing the piston 33 and crown 38, the finger piece and piston engaging rod 34 are revolved to compress the pis- 100

ton to force soap through the bore of the cap piece stem 13 to discharge through the bristles 40 of the brush 25. A suitable lather is worked up on the face of an operator by manipulation of the brush bristles. The convex conformation of the head piece prevents interference from the brush bristles while shaving.

While I have described and illustrated the invention as comprising the preferable plane faced pliable blade, it is evident that a convex blade might be utilized, crimping of the blade into an isomorphic convex disposition to the head structure proper, being eliminated. Further structural modifications are believed evident, and I do not wish to confine myself to the specific disclosure, except as hereinafter limited by the scope of the appended claims.

20 What I claim, is:—

1. In combination with a safety razor having a head forming a convex configuration in horizontal and transverse vertical section with a cutting edge adjacent the extremity of each of said head forming arcs, of a flexible brush carried by said head, a soap containing handle detachably engageable to said head, and means to discharge the soap from said handle to the brush.

2. The combination with a safety razor providing a head adapted to engage a razor blade having multiple cutting edges, said head being formed in a convex configuration wherein the cutting edges of the blade lie adjacent the respective arc terminals, of a flexible brush carried by said head and disposed substantially centrically of the head arc, a hollow handle for said head, means to insert a soap cartridge within said handle, and means to discharge the soap from said handle to the brush.

3. The combination with a safety razor having a head adapted to engage a razor blade, said head being formed in a convex configuration and wherein the cutting edge of the blade lies adjacent a terminal of said head arc, of a flexible brush carried by said head, a soap containing handle for said head, and means to discharge the soap from said handle to the brush.

4. The combination in a shaving device having a cutting head formed of a convex cross-shaped cap piece providing a centrically disposed screw-threaded hollow stem, a barrel handle having a tubular shank engageable with said stem, a convex cross-shaped backing plate for said cap piece, and a plane faced resilient blade arranged for interposition between said cap piece and plate for clamping engagement therebetween, said cap piece presenting studs projecting radially from the center of the same about said stem, the blade and backing plate providing 65 annulets aligned with said studs for engage-

ment thereover, of a brush disposed centrically of the arcuate peripheries of said convex cap piece, a soap cartridge carried within said barrel handle, and means to discharge soap from said cartridge to the brush.

5. The combination in a shaving device having a head comprising a guard and a cap piece, said head being adapted to detachably support a cutting blade between said guard and the cap piece, of flexible lathering means carried by said cap piece, a soap-containing handle for said head, and means to discharge the soap from said handle to the lathering means.

6. The combination with the cutting head of a safety-type shaving device, said head comprising a guard and a cap piece, said guard and cap piece being adapted to support a cutting blade therebetween, of flexible lathering means carried by said cap piece for lathering the face.

7. The combination in a shaving device having a head comprising a guard and a cap piece, said head being adapted to detachably support a cutting blade between said guard and the cap piece, of a brush composed of a plurality of flexible bristles carried by said cap piece for lathering the face.

Signed at Seattle, Washington, this 1st day of October, 1929.

FREDERICK T. HOPE.
